UNITED STATES PATENT OFFICE.

NORMAN JACOBSEN, OF PARIS, FRANCE.

PRINTING PROCESS BY MEANS OF SUPPORTS WITH ROUGH SURFACES.

Application filed August 5, 1926, Serial No. 127,449, and in France August 12, 1925.

The present invention has for its subject a process for the preparation, with a support (such as a sheet of paper) with a rough surface, a sheet by means of which it is possible to print drawings, engravings and so forth having the appearance of lithographs or wood engravings. In the preferred method of carrying out the invention the support with the rough surface in question is simply formed by a sheet of sand paper or other similar product with a sufficiently fine grain. Such a surface, when inked by means of a roller coated with printing ink in accordance with the method usually employed for lithographic printing, has the property of rejecting the ink, the latter only adhering in very small quantities to the grains which are distributed over the surface of the support.

Among the objects of the invention are to provide a printing means comprising a sheet having portions composed of exposed sand paper and other portions consisting of a smooth substance embedded in and overlying the sand paper. This smooth substance is preferably a fatty body and, in the improved embodiments of the invention, either wax grease may be employed.

A further object is to provide a method of preparing a rough-grained surface suitable for printing, consisting in drawing the drawing to be produced by means of a fatty substance on a surface and transferring the drawing thus produced by pressure to the rough-grained surface of sand paper so as to render this surface smooth and continuous at the portions corresponding with the black portions in the print to be obtained.

The accompanying drawing shows diagrammatically various methods of carrying out the process forming the subject of the invention.

In the most simple form of carrying out the invention for the purpose of obtaining prints having the appearance of lithographs there are formed on the rough grained surface of the sand paper by means of a grease pencil smooth and continuous lines or surfaces capable of retaining printing ink. Figure 1 shows to an enlarged scale an example of this method of carrying out the

invention. Figure 2 is a section on the line II-II of Figure 1. In these Figures 2 indicates the parts treated so as to enable them to retain the ink. Figure 3 is a cross section of a modification of my invention together with an imprint of a part of the printing surface.

The procedure for the production of engravings with fine lines is as follows: The drawing to be reproduced is drawn on a sheet of gelatine or on a sheet of paper coated with gelatine by means of liquid wax, the drawing in question being made by means of any suitable instrument and the wax is maintained at the necessary degree of fluidity by means which are also known. The drawing thus obtained is transferred to the rough grained surface of the sand paper by simple pressure which is conveniently exerted by means of the printing machine itself. The drawing may also be drawn on an ordinary sheet of paper and then all the lines of the drawing are run over with wax; the reproduction of the drawing is effected in the same manner. In order to obtain an efficient drawing whether the drawing has been drawn on gelatine or on ordinary drawing paper the gelatine or the paper, before making the drawing in wax, is preferably coated with a suitable adhesive substance. Egg albumen is very suitable for this purpose and gives the best results.

In order to obtain prints having completely white portions, for the purpose of obtaining effects opposite to black or white entirely similar to those obtained by a wood engraving, the portions which are to remain white are cut from the sheet of sand paper as shown at *b* in Figure 3. When the sheet is mounted on a block of wood for printing, this block, as is well understood, should be notched and hollowed at the point of the openings formed in the sheet of sand paper. A similar result may be obtained by treating the sheet of sand paper in such a manner that the pressure is reduced at the points where the print is to have white portions. For this purpose the grained portions at these points may, for example be scraped away or hollow portions may be formed at these points.

It will be understood that the invention

enables prints of any colour to be obtained or even multi-colour prints by means of a number of sheets suitably prepared for this purpose and carefully arranged during printing in the well known manner.

Having thus described my invention, what I claim as new and desire to secure by Letters Patent is:—

1. A method of preparing a rough grained surface suitable for printing consisting in drawing the drawing to be reproduced by means of liquid wax on a surface, and then transferring the drawing thus produced by pressure to the rough grained surface of glass paper so as to render this surface smooth and continuous at the portions corresponding with the black portions in the print to be obtained.
2. A method of preparing a rough grained surface suitable for printing consisting in drawing the drawing to be reproduced by means of liquid wax on a surface, coating the surface with an adhesive such as egg albumen, and then transferring the drawing thus produced by pressure to the rough grained surface of glass paper so as to render this surface smooth and continuous at the

portions corresponding with the black portions in the print to be obtained.

3. A printing means comprising a sheet having portions composed of exposed sand paper and other portions consisting of a smooth substance embedded in and overlying the sand paper.

4. A printing means comprising a sheet having portions composed of exposed sand paper and other portions consisting of a fatty body embedded in and overlying the sand paper.

5. A printing means comprising a sheet having portions composed of exposed sand paper and other portions consisting of wax embedded in and overlying the sand paper.

6. A method of preparing a rough-grained surface for printing, consisting in drawing the drawing to be produced by means of a fatty substance on a surface and then transferring the drawing thus produced by pressure to the rough-grained surface of sand paper so as to render this surface smooth and continuous at the portions corresponding with the black portions in the print to be obtained.

NORMAN JACOBSEN.
